AUTOMATIC REGISTER

Filed Feb. 16, 1922

2 Sheets-Sheet 2

UNITED STATES PATENT OFFICE.

PHILIP A. JACKSON, OF ATLANTA, GEORGIA, ASSIGNOR TO THE EGRY REGISTER COMPANY, OF DAYTON, OHIO, A CORPORATION OF OHIO.

AUTOMATIC REGISTER.

Application filed February 16, 1922. Serial No. 537,079.

This invention has reference to automatic registers, and its object is to provide a device for causing duplicate copies of a bill or memorandum for the transaction of the business, the device being adapted to rest upon a counter or other support and to contain numerous rolls of paper with carbon sheets between them so that when the bills are made out, all the bills may be torn off, or one copy 5 may be rewound in the device and the other or others (one original and a copy), are capable of severance from the rolls for presentation to a customer and for other purposes.

15 With respect to the rolls of paper, the invention need not differ from autographic registers already in use, but the invention differs from prior devices in that the duplicate bills are brought into register, irrespective of their length, within certain limits, due to the presence of certain devices, for 20 when the sheets are released they align themselves by natural recoil aided by gravity means.

25 The invention will best be understood from a consideration of the following detailed description, taken in connection with the accompanying drawings forming part of this specification, with the understanding, 30 however, that the invention is not confined to any strict conformity with the showing of the drawings, but may be changed and modified so long as such changes and modifications mark no material departure from 35 the salient features of the invention as expressed in the appended claims.

In the drawings:

Figure 1 is a side elevation of the register. 40 Figure 2 is a longitudinal, vertical section thereof, showing an appropriate number of rolls of paper therein.

Figure 3 is a diagram of the arrangement shown in Figure 2 but omitting some details.

Figure 4 is a plan view of the machine 45 of Figure 1.

Figure 5 is a view, partly in elevation and partly in horizontal section, of a wind-up roll and adjacent structure.

Figure 6 is a section on the line 6—6 of 50 Figure 2.

Figure 7 is a detail view of one of the gravity devices for tensioning the paper.

Figure 8 is a detail view of a gravity member for traversing matching punch holes in the paper sheets.

55

Referring to the drawings, there is shown a casing 1, such as is ordinarily provided in autographic billing registers. This casing is furnished with a depressed writing table 2, over which superposed sheets 3 are caused to travel, such sheets being customarily paper sheets and furnished in rolls 4 of appropriate length and width, the rolls of paper being wound upon spools 5, journaled in the sides of the casing under slight tension to prevent overrunning of the spools in unwinding and to aid recoil and alignment. In the particular structure shown, there are three sheets of paper, but the number of sheets may vary. At the right hand end of the casing 1, as seen in the drawings, and arranged in a series of three, are idler rollers 6 capable of individual movement in slanting recesses 7. The rollers may be mounted in frames 8 and the cross-bar of said frames are just in front 75 of idlers 6 but do not interfere with the passage of the paper. These frames 8 are provided with side arms that are bent down at ends and pivoted to the sides of the casing, so that the rollers may, in any case, have a 80 normal tendency to gravitate toward the bottoms of the recesses 7 of the frames 8, or they may roll independently in the recesses without the frames 8. The idler rollers 6 are fixed in frames 8 and in loading the 85 register frame the idlers are lifted clear. Each web 3 of paper is carried about a respective idler roller after coming from the roll 4 of papers and then returned to the opposite end of the casing 1 over the table 2. 90 After passing over the table 2, the group of paper sheets 3 is continued, with the sheets in superposed order, beyond a tearing edge 10, or other means, whereby the group of sheets or all but one sheet to be retained, 95 may be severed at will. In the last named case, one sheet 3a, constituting the lowermost one of the group of sheets, is not continued past the tearing edge 10, but is directed into the interior of the casing 1, to be 100

ultimately wound on a storage roller or drum 11, housed in the casing 1, so as to retain locked within the casing, a record of the bills produced in the usual manner upon the sheets traversing the table 2.

After leaving the writing table 2, the sheets 3 pass between a feed gripping roller 12 within the casing and another feed roller 13, containing within a housing 14 on the top of the casing and extending transversely thereof. The roller 13 is mounted on trunnions 15, and these trunnions are mounted in elongated guides 16 at opposite ends of the roller 13. Each guide 16 has a rod-like extension 17 slidable through a fixed bracket 18 fast to the corresponding side wall of the casing, and the extension 17 is surrounded by a spring 19 tending to draw the roller 13 toward the roller 12, whereby to grip the sheets 3 between said rollers 12 and 13. In this manner, on rotating the roller 12, and with the springs 19 free to act, the rollers 12 and 13 operate as feeding rollers on imparting relative movement to the roller 12. Such movement is accomplished by means of a crank 20, fast on a shaft 21 carrying the roller 12 and journaled in the side of the casing wall. The guides 16 are mounted to slide between ribs 22, suitably spaced apart on the inner wall of the casing 1 to receive the guides 16 and permit variation in the distance between the rollers 12 and 13. At the end portion of the roller 12 are camlike projections 23, preferably made detachable and adjustable and so located as to be out of the path of the superposed sheets 3, whereby every time the roller 12 is rotated a sufficient distance, say one revolution, the cam-like projections 23 will engage the roller 13, thus lifting it away from the sheets 3, and releasing them. The circumference of the drum 12 is slightly greater than the length of the bills, aside from the space taken up by the cams 23, for the purpose of allowing for the recoil and alinement of said bills.

At one end of the roller 12 there is provided a gear wheel 24 rotatable with the roller 12 and meshing with an idle gear wheel 25, which carries pawl 30, mounted on a stud 26, carried by the frame 1, these parts being best shown in Figure 5, and also appear in Figure 2. The stud carries a ratchet wheel 27, to which there is made fast a gear wheel 28, while on the adjacent wall of the casing 1 is a pin or stud 29, in the path of a trip pawl 30, fast to gear wheel 25, which may have a normal constraint by reason of a spring 30^a, for constant one-way engagement with the ratchet 27, except when engaged by the pin or stud 29. The gear wheel 28 is in mesh with another gear wheel 31, with a friction pull to the drum 11, the arrangement being such that when the drum or roller 12 is rotated by the handle 20 in

the proper direction, motion is transmitted through the gear wheel 28 to the drum 11, by friction pull 31, thereby winding the record sheets 3^a upon the drum 11, to preserve a record within the register of the writing produced on the table 2. The drum 11 has frictional connection with the gear wheel 31 to be intermittently rotated by the latter when the handle 20 is actuated, as the said drum must travel faster than the bills 75 are driven by the rollers 12 and 13.

The sheets 4 have pairs of punch holes near the center thereof to receive pins 32 pivoted on a rock shaft 33, and located near the center of the casing 1, so as to traverse 80 the punch holes in the sheets 4, these pins having beveled or similarly shaped ends 34, best shown in Figure 2. The beveled ends 34 permit the paper sheets to override the pins as the rollers 12 and 13 feed the paper 85 sheets forwardly, the gravity rollers 6 participating in this forward movement. The projections 23, when they reach the rollers 13, lift it away from the roller 12, thus releasing the sheets 4, whereupon the rollers 6, riding down the inclined surfaces 7, return the rollers 6 and pull the sheets against the pins 32 in such manner that all the sheets then traversed by the pins are brought into register automatically. This application is facilitated by providing the rock shaft 33 with counterweights 35, tending at 90 all times to press the pins 32 upwardly. As paper is drawn over 32 it is pressed down until punch holes are brought over point of 95 32 and pins 32 press upwardly through punched holes for perfect alinement.

Manifestly the pins 32 have their front surfaces perpendicular to prevent lost motion, while the bevel at the top of the pins 32 is to allow bills after being alined on pins 32, to automatically ride over the pins in a forward direction, otherwise the bills would jam on the tops of pins. It will be seen that the pins 32, may be arranged close 105 up in front of gripper rollers or in rear of gripper rollers so long as they are in alignment with punch holes.

The crank 20 is provided with a yieldable pin 36, movable at one phase of the rotation 115 of the crank, against an inclined surface 37 having a notch into which the pin 36 may temporarily snap and from which the pin 36 may be withdrawn to allow further rotation of the crank.

At one side of the casing 1, there is a holder or pocket 38, in which may be lodged sheets 39, of carbon or other impression paper, extending crosswise of the path of movement of the sheets 3, between the latter, so that writing produced upon the outermost sheet of paper will provide impressions on the other sheets thereunder, this being a feature common in billing registers, and so requires no particular description.

The sheets 3 of paper, together with the carbon sheets 39, are threaded through the machine in the usual manner. When a bill or memorandum is to be produced it is written upon the outermost one of the sheets covering the table 2 and the crank 20 is then manipulated to feed these sheets beyond the tearing edge 10 with the exception of the lowermost sheet 4^a, which on the turning of the crank 20 is wound upon the drum or roller 11 to form a part of the retained or locked-in-record, the other sheets being torn off at the tearing edge 10 in order to provide a copy for the customer and another copy when desired, for file copy, these features being common to billing registers.

All bills are freed at the same time by the tripping action of the pawl 30, and the action of the cams 23, said bills being caused to align by reason of the punch holes surrounding the pins 32, the recoil of the said bills resulting from the backward pull of the rollers 6 drawing the same taut and in perfect alignment, it being understood that the pawl 30, cams 23 and rollers 6 act at the same time that the pins 32 automatically enter through the proper punch holes. But tipping of pawl 30 must begin slightly in advance of action of cams 23 to stop drum 11 and to allow slack in record sheet for recoil, and aligning with other sheets. However, the parts are so timed that before the tearing operation is performed, the roller 13 is lifted out of feeding contact with the roller 12 and pawl 30 is tripped by the stud 26 releasing the sheets and permitting the gravity rollers 6 to have a short return movement, with the pins 32 in engagement with the sheets, to return the several sheets into register, after which the sheets are again engaged by the rollers 12 and 13, and held while being brought into engagement with the tearing edge 10 in order to sever those sheets which it is intended should be removed from the register while leaving the lowermost sheet in position. The registering of the several sheets occurs while these sheets are released by the rollers 12 and 13

when the stud 26 trips the pawl 30, and the tearing of the sheets occurs when the rollers 50 have returned to clamping relation to the sheets.

The invention provides for the matching or registering of the sheets upon which the bill or other record is produced by means of 55 the pins 32 and the overrunning and the return of the bills for a minute distance, resulting in the feeding of the sheets into tearing position. The mechanism for this purpose is peculiar to this invention. 60

Having described my invention, what I claim and desire to secure by Letters Patent is:

1. In an autographic register for feeding a plurality of paper sheets having spaced 65 series of perforations, feeding rollers, means to actuate said rollers to feed said sheets, means to separate said rollers to interrupt the feeding of said sheets, means to automatically align said sheets comprising pins 70 to receive the perforations in the sheets after they have passed through the feeding rollers and rollers adapted to draw the sheets back against said pins during the separation of said feeding rollers, the several steps in the 75 operation consisting of feeding the desired length of sheets and realigning the sheets ready for the next operation being automatically performed by one revolution of the actuating means. 80

2. In an autographic register for feeding a plurality of paper sheets having spaced series of perforations, brackets pivotally mounted in the side walls of said register adjacent openings therein, a roller mounted 85 in each of said brackets, said openings having the lower edges thereof inclined toward the front of the register, whereby the rollers may be moved forwardly when the paper is being fed and returned by gravity rearwardly when the feeding of the paper ceases, the movement of the rollers being limited by said openings. 90

In testimony whereof I have hereunto set my hand.

PHILIP A. JACKSON.
